UNITED STATES PATENT OFFICE.

WILLIAM R. RAY, OF SAN FRANCISCO, CALIFORNIA.

AUTOMATIC FUEL CUT-OFF FOR OIL-BURNERS.

1,247,149.

Specification of Letters Patent. Patented Nov. 20, 1917.

Application filed May 8, 1916. Serial No. 96,109.

To all whom it may concern:

Be it known that I, WILLIAM R. RAY, a citizen of the United States, residing at the city and county of San Francisco and State 5 of California, have invented new and useful Improvements in Automatic Fuel Cut-Offs for Oil-Burners, of which the following is a specification.

This invention relates to automatic fuel 10 cut-off for oil burners.

The present invention illustrates an oil burner of the rotary type described in my pending application, Serial No. 874754, filed November 30, 1914, entitled "Oil 15 burners."

This burner consists of a casing supporting an electric motor, a direct connected air fan and a centrifugal atomizing cup to which fuel oil is delivered from any suitable 20 source such as a pump or a gravity supply.

It sometimes happens that an accident to the motor or a temporarily closing down of the main power line renders the motor with connected fan and atomizer, inoperable. 25 Under such circumstances, it can readily be seen that means must be provided for automatically cutting off the fuel supply to the atomizer as it would only be a matter of time when the oil delivered would flood the 30 furnace and either cause an explosion or overflow into the surrounding quarters where a fire might possibly be started.

The object of the present invention is to overcome this danger by providing a mechanism which will automatically cut off the fuel supply to the atomizer the moment the fan slows down below a certain number of revolutions per minute or stops entirely.

Further objects will hereinafter appear.

40 The invention consists of the parts and the construction and combination of parts as hereinafter more fully described and claimed, having reference to the accompanying drawings in which—

45 Figure 1 is a side elevation of the oil burner partly in section, showing the application of the invention.

Fig. 2 is a vertical central section of the diaphragm.

50 Referring to the drawings in detail, A indicates an ordinary furnace front and 2 a casing secured thereto in any suitable manner, which forms a support for an electric motor 3, an air fan 4 and a centrifugal atomizer 5. The motor is in this instance provided with a hollow shaft 6, one end of

which is sufficiently extended to form a support for the fan 4 and the atomizer 5. The casing 2 not only forms a support for the motor 3 but also serves as a housing for the 60 fan. Formed on the inner side of the housing is a nozzle 7 which surrounds the atomizing cup 5. Air entering the fan, when revolved by the motor, first passes through the housing 2 and then through an annular 65 air passage 8, formed between the nozzle 7 and the atomizer 5. The air thus admitted is employed for a double purpose. First to assist in atomizing the oil discharged from the atomizer 5 and second, to support combustion within the furnace. The oil delivered to the atomizer 5 passes through a pipe 9 connected with a suitable source of supply. It then passes through a passage formed in a hollow pindle 10; a pipe 11 and a valve 12 70 which is interposed between pipe 11 and a stationary pipe 13 extending through the hollow shaft of the motor and opening into the atomizing cup 5. The peculiar arrangement of the pipe connections supplying the 75 oil to the atomizer 5 is made for the purpose of permitting a swinging movement of the casing 2 with relation to the furnace front. It however, forms no part of the present invention. By referring to Fig. 1, it will be 80 seen that the furnace front is provided with a plate 14, to which the casing 2 is secured by means of the hinges 15. It is thus possible to swing the casing 2 with the attached motor, fan and nozzle to and from the furnace front without disturbing the pipe connections.

The foregoing description shows that the oil supplied to the atomizer 5 is independent of the motor with connected fan and atomizer and that slowing down of the motor or stoppage of same caused by accident to the power line or otherwise, would not affect the fuel supply. In other words, it would be possible for the motor with connected fan 95 and atomizer to stop, without affecting the flow of oil to the atomizer. Under such circumstances, it can readily be seen that means must be provided for automatically cutting off the fuel supply to the burner as 100 it would only be a matter of time before the oil would flood the furnace or overflow into the surrounding quarters. This is accomplished in the present instance by the following mechanism.

110 Suitably secured at any convenient point with relation to the furnace and the burner

as a whole, is a diaphragm valve which is generally indicated at B. This valve consists of a casing 16 provided with a cover 17 between which and the casing 16 is mounted 5 a diaphragm 18. Casing 16 is sufficiently large to permit the formation of an interior pressure chamber 19. This chamber is connected with the fan casing 2 by means of a pipe 20. Secured to one side of the dia- 10 phragm 18, and extending through the cover, is a rod 21, the outer end of which is slotted as at 22, to straddle a locking lever 23 pivotally mounted as at 24 to the lower end of the cover 17. The upper end of this 15 lever is connected to the casing 16 by means of a coil spring 25, the function of which will later be described. The lower end of the lever 23 is notched as at 26 to form a seat for a pin 27 secured on a weighted lever 20 20 28 connected with a cut-off valve 29 interposed between the pipe 9 and the hollow pintle 10.

In operation, when it is desired to start a fire in the furnace, it is only necessary to 25 start the motor 3 by throwing in a connected switch not here shown. This will immediately start the fan and connected atomizing cup 5 to revolve as these are directly connected to the motor and as the speed increases, an air pressure will be created in the housing 2. This pressure is immediately transmitted to the diaphragm as the chamber 19 is connected with the casing by means of a pipe 20. Pressure thus admitted causes 30 35 the diaphragm 18 to expand or assume the full line position shown in Fig. 2. The rod extension 21 carried by the diaphragm will then force the lever 23 away from the cover and cause it to assume the full line position 40 shown in Figs. 1 and 2. The weighted lever controlling the position of the valve 29 may now be raised until the pin 27 is engaged by the notch 26 formed in the lower end of the lever. This position of the valve 29 is 45 open to permit the fuel oil to pass through the pipe line and the connections herebefore described to a point where its flow is regulated by valve 12 before it is finally admitted to the atomizer 5. The diaphragm will remain 50 in the expanded position as long as the motor, with connected fan, is rotating above a certain number of revolutions per minute but the tension of the spring 25 connected with the upper end of the lever 23 is sufficient to overcome the air 55 pressure in the chamber 19 the moment the motor, with connected fan, slows down below a certain number of revolutions per minute or stops. The lever will thus be retracted to resume the dotted line position indicated at 23^a, see Fig. 2. The pin 26 will thus be released and the weighted lever will be permitted to drop and assume the dotted line position shown at 28^a, thus closing the 60 65 valve 29 and cutting off the fuel supply to

the atomizer the moment the motor, with connected fan, stops or slows down below a certain number of revolutions per minute. When the lever 23 and the weighted lever 28 are in engagement, the weight of the lever 28 is applied to the lever 23 in conjunction with the spring 25 to force the diaphragm 18 inwardly against the air pressure against the diaphragm. The tendency of the weighted lever is to swing down out 70 of engagement with the lever 23, so that as soon as the pressure in the valve B drops below normal, the weight of the lever 28 alone is sufficient to cause the pin 27 to escape the notch 26, so that the lever will drop 75 and close the valve 29. It will thus be seen that the spring 25 and the weight of the lever 28 both serve to disengage the pin 27 from the notch 26 to enable the lever 28 to close the valve 29 when the pressure in the 80 valve B drops below normal, thus doubly insuring certain and positive operation of the device. Any danger of explosion within the furnace caused by an over-supply of oil or flooding or ever-flowing into surrounding quarters is thus obviated as the fuel supply is automatically cut off. The pipe 20 forming a connection between the housing 2 and the pneumatic valve chamber 19 is connected with a hollow pintle 30 which 85 in turn is connected through a pipe 31 with the interior of the fan housing. This peculiar arrangement of the pipe connections is, as previously described, provided for the purpose of permitting the casing with attached motor fan and atomizer, to swing about the hinges 15 without breaking or disturbing either the air or oil pipe connections. The diaphragm valve as a whole is simple in construction and easy to attach. While it 90 95 100 is here shown as arranged directly above the burner, it is obvious that it may be placed at any convenient point within the furnace room without materially changing the connections here shown. 110

The materials and finish of the several parts of the invention may be such as the judgment and experience of the manufacturer may dictate.

I wish it understood that various changes 115 in form, proportions and minor details of construction may be resorted to within the scope of the appended claims and that I do not wish to limit myself to the specific design and construction here shown.

Having thus described my invention, what I claim and desire to secure by Letters Patent is—

1. In combination, oil-supply means and air-supply means, a cut-off valve for controlling said oil-supply means, a diaphragm adapted to be actuated by the air pressure of said air-supply means, a pivoted locking lever actuated by said diaphragm and formed with a seat, and a weighted operat- 125 130

ing lever for said cut-off valve having a laterally extending pin for engaging in the seat of the locking lever to hold said weight-ed lever releasably.

- 5 2. In combination, oil-supply means and air supply means, a cut-off valve for controlling said oil-supply, a casing connected with the air supply means, pressure-operated means in the casing including a slidable stem having its outer end slotted, a locking lever pivoted between its ends to one side of the casing and engaged in the slotted end of the stem, a spring connecting one end of the lever to the opposite side of the casing, and means releasably engaging the opposite end of the lever for operating the valve.
- 10 3. In combination, oil-supply means and air supply means, a cut-off valve for controlling said oil-supply, a casing connected with the air supply means, pressure-operated means in the casing, a locking lever pivoted to the casing and formed with a notch in one edge, said lever being operable by the pressure-operated means, a lever for operating 25 the valve mounted for swinging alongside of
- the locking lever in a plane substantially parallel with the plane of movement of said locking lever, and a laterally extending pin carried by the valve lever for engaging detachably in the notch of the locking lever. 30
4. In combination, oil-supply means and air supply means, a cut-off valve for controlling said oil-supply, a casing connected with the air supply means, pressure-operated means in the casing, including a stem having 35 its outer end formed with a seat, a lever pivoted on the casing and freely engaging in the stem seat, a spring connecting the lever to the casing and tending to hold the lever in its seat, and means for controlling 40 the valve releasably locked open by said locking lever.

In testimony whereof I have hereunto set my hand in the presence of two subscribing witnesses.
